UNITED STATES PATENT OFFICE.

THOMAS J. MCKAY, OF ATLANTA, GEORGIA.

OIL-COOK-STOVE LID AND FENDER.

1,330,643.

Specification of Letters Patent. Patented Feb. 10, 1920.

Application filed July 15, 1919. Serial No. 311,008.

To all whom it may concern:

Be it known that I, THOMAS J. MCKAY, a citizen of the United States, and a resident of Atlanta, in the county of Fulton and 5 State of Georgia, have invented a new and Improved Oil-Cook-Stove Lid and Fender, of which the following is a full, clear, and exact description.

This invention relates to attachments for 10 oil cook stoves and has for an object to provide an improved structure in which means are provided which will prevent soup or other matter from falling on the chimney or into the top of the chimney and extinguishing the flame.

Another object of the invention is to provide an attachment for oil cook stoves arranged with means presenting a support for a pot or other articles and a removable fender for directing anything falling through the support to a point away from the chimney of the burner.

A still further object of the invention is to provide an attachment including a lid 25 formed with supporting rings arranged to prevent an inward flow of liquid which may be boiled over or caused to overflow from a container on the lid.

In the accompanying drawing:

30 Figure 1 is a fragmentary sectional view through an oil cook stove with an attachment embodying the invention shown applied thereto, the attachment being shown in section, taken on line 1—1 of Fig. 2.

35 Fig. 2 is a top plan view of the attachment illustrated in Fig. 1.

Fig. 3 is a fragmentary detail bottom plan view of one of the supporting arms of the attachment shown in Fig. 1.

40 Fig. 4 is a detail fragmentary side view showing an arrangement of support for the deflector illustrated in Fig. 1.

Referring to the accompanying drawing by numerals 1 indicates an oil cook stove of 45 any desired kind provided with a burner or chimney 2 and a top 3. The top 3 has a number of lid openings 4 which are adapted to receive the lids 5 formed according to the present invention, said lids supporting 50 fenders 6 also forming certain features of the invention. The lid 5 is formed of a number of rings 7 as shown in Fig. 2 through which radiating bars 8 extend. These bars are connected to the innermost

ring 7, but extend beyond the outer ring 7 55 and are flattened at 9 so as to produce a shoulder used in centering the lid 5 and also preventing the outer ring 7 from engaging the walls of opening 4. This will always allow anything falling on the lid to 60 pass through between top 3 and the lid. The lid may be built up of many parts and bars 8 extend through suitable openings or the entire construction may be cast in one piece. In either event the construction is as shown, 65 which presents means for supporting a pot or container of any kind, and which in addition act as deflecting rings to prevent any overflow of the food or soup of any kind from entering the top of the chimney 70 2 or falling on it. In order to absolutely prevent any soup boiling over the container from entering the chimney 2 fender 6 is connected with the lid 5, said fender being slightly cupped and formed with a central 75 aperture 10. An upstanding flange 11 is arranged at aperture 10 so as to either telescope into or almost telescope into the inner ring 7 of lid 5 while the outer edge 12 extends an appreciable distance beyond the 80 chimney 2, any liquid passing between any of the rings 7 will be guided by the fender 6 and diverted a sufficient distance to one side to escape the chimney and fall into the base 13. In order to hold the fender 6 85 properly in place any desired number of hook members 14 are provided which are riveted or otherwise rigidly secured to the fender 6 and formed so as to hook over certain of the bars 8 as shown in Figs. 2 and 4. 90 By this construction and arrangement the fender may be quickly and easily removed and washed at any time.

In operation, when the parts are arranged as shown in Fig. 1 and a container containing food is placed thereon, it will be heated in the usual manner, the flame from the chimney passing through the opening 10 and spread freely through the ring 7 in the usual manner. In case the soup should boil 100 over the escaping soup would pass through rings 7 and either strike the fender 6 or pass a sufficient distance from the chimney not to in any way interfere with the proper operation thereof.

105 What I claim is:

The combination with an oil cook stove burner and chimney of a removable lid

formed with a plurality of concentric spaced rings and a plurality of spaced radiating bars extending centrally through all of said rings and beyond the outer ring so as to overlap the top of the stove, a cup-shaped fender having a central opening positioned beneath said lid with a central opening in

line with said chimney, and a plurality of hooks rigidly secured to the fender formed with the hook portion open so as to be capable of being bodily applied and removed from certain of said radiating bars without disturbing the lid. 10

THOMAS J. MCKAY.
